THE NORRIS PETERS CO., PHOTO-LITHO., WASHINGTON, D. C.

UNITED STATES PATENT OFFICE.

MICHAEL H. MCKENNA, OF CLEVELAND, OHIO.

MACHINE FOR BENDING METAL BARS.

1,277,234.

Specification of Letters Patent. Patented Aug. 27, 1918.

Application filed October 13, 1917. Serial No. 196,355.

To all whom it may concern:

Be it known that I, MICHAEL H. MCKENNA, a citizen of the United States, residing at Cleveland, in the county of Cuyahoga and State of Ohio, have invented certain new and useful Improvements in Machines for Bending Metal Bars, of which the following is a specification.

This invention relates to machines for bending metal, and especially metal bars of that type employing a bed or table on which the work is held, and a pivoted bender which by its turn bends the metal around suitable formers to give the desired angle.

15 The object of the invention is to improve the means for operating a pivoted bender, said means including a shaft, and a clutch-device which is controlled by hand to operate the shaft and automatically released 20 at the end of the stroke.

A further object of the invention is to improve the particular formers and the devices employed in the machine.

In the accompanying drawings, 25 Figure 1 is a plan of the machine showing the bar inserted, before being bent.

Fig. 2 is a similar view showing the bend completed.

Fig. 3 is a side elevation of the machine.

30 Fig. 4 is a section on the line 4—4 of Fig. 3.

Fig. 5 is a vertical section on the line 5—5 of Fig. 1.

Fig. 6 is a detail in elevation of the latch 35 device.

Fig. 7 is a plan of modification.

Referring to the drawings, 1 indicates a base covered by a plate 2, and 3 is a bed or table supported on the posts 4.

40 The table has a circular slot 18 for a purpose to be described. 5 is a shaft which is mounted in a step bearing 6 on the base, and its upper end turns in and projects through a bearing plate 7 fastened to the

45 table. Loose on the shaft 5 is a gear 8, and keyed to the shaft directly above the gear is an arm 10. The gear 8 has a series of up-standing lugs 9 at the edge, and the outer end of the arm 10 has a shoulder 11 and a 50 radial pivot 12 upon which is mounted a rocking latch indicated as a whole at 13. This latch has a hub 14 which fits over the pivot and a hook part 16 which projects laterally in position to catch one of the lugs 55 9 when the latch is swung one way, thus

clutching the gear 8 and the arm 10 and turning the latter and the shaft 5, the gear 8 being constantly driven. The latch includes a handle 17 which projects through 60 the slot 18 above the top of the table. 19 is a lug projecting from the hub 14 and adapted to stop against a support 20 on the arm 10 when the latch is thrown back or out. The arm 10 may be reversed for right or 65 left movement by separating the same at its shank 21 and turning it around half way on the shaft 5, the latch 13 then being reversed, wherefore two stops 20 are provided on the arm 10, as shown in Fig. 4, the operating gear 70 or motor being modified or reversed accordingly.

At 22 is indicated a shaft mounted on the bottom plate under the table, and carrying a pinion 23 meshing with the gear 8 75 and also a gear 24 which meshes with a pinion 25 on a shaft 26 which carries a beveled gear 27 meshing with a bevel pinion 28 on a horizontal shaft 29 mounted in bearings 30 and 31. This shaft 29 carries a spur 80 gear 32 driven by pinion 33 on the shaft of the motor 34.

If desired the motor may be omitted and the shaft 29 provided with fast and loose 85 pulleys 35 and 36 driven by belt from any suitable power, with a belt shifter 37 to control the drive.

The upper end of shaft 5, above the table carries an arm 38 provided with a stud 40 and bending roller 41. The stud may be 90 set in any one of the holes 39 in the arm to vary the bend. The shaft 5 also carries a central forming roller 42, at the top of the shaft. The bearing plate 7 has a bracket 43 with holes 44 therein to receive a stud 95 on the abutment block 45 which may be adjusted to present any of its several faces to the bar to be bent. 46 is a stop or knockout block which may be set at adjustment in the slot 18 and fixed by bolt 47.

100 In operation the bar, to be bent is placed between the benders 41 and 42 and against the abutment 45, as shown in Fig. 1. The handle 17 is then thrown forward, causing the latch hook 16 to engage one of the lugs 105 9. This picks up the arm 10 and shaft 5, swinging the arm 38 and bending the bar around the former 42. At the end of the desired bend the handle 17 strikes the stop block 46 and lifts the latch, thereby disconnecting the shaft from the gear. The arm 110

10 may then be swung back by pressure on the handle 17, the bent bar removed, and another bar inserted for the next operation.

Various changes in the work produced are permitted by varying position or size of the block 45 and formers 41 and 42. The clutch or latch connection between the constantly driven gear and the bending shaft permits rapid operation upon the successive pieces 10 of work, without stopping the motor.

I claim:

1. In a metal bending machine, the combination of a table having a work holder thereon and an arcuate slot therein, a shaft projecting through the table and having a bending arm above the same, a driving wheel loose on the shaft below the table, an arm fixed to the shaft, and a catch pivoted on the last mentioned arm and engageable with the 20 wheel to turn the shaft, said catch having

an operating handle projecting upwardly through the slot in the table and movable in said slot when the arm swings.

2. In a metal bending machine, the combination of a table having a work holder and 25 an arcuate slot therein, a shaft projecting through the table and having a bending arm above same, a driving gear below the table, and a clutch device between the gear and the shaft, having an operating handle projecting through the slot and a stop adjustable along the slot to engage the handle at the end of stroke and release the clutch.

In testimony whereof I do affix my signature in presence of two witnesses.

MICHAEL H. MCKENNA.

Witnesses:

JOHN A. BOMMHARDT,
G. W. ROSENBERG.
